United States Patent Office.

STEPHEN CHAMBERLIN, OF BOSTON, MASSACHUSETTS.

Letters Patent No. 70,957, dated November 19, 1867.

IMPROVEMENT IN TIP-WAGON.

The Schedule referred to in these Letters Patent and making part of the same.

TO ALL WHOM IT MAY CONCERN:

Be it known that I, STEPHEN CHAMBERLIN, of Boston, in the county of Suffolk, and State of Massachusetts, have invented an improved Tip-Wagon; and I do hereby declare that the following, taken in connection with the drawings which accompany and form part of this specification, is a description of my invention sufficient to enable those skilled in the art to practise it.

The invention relates to the construction of four-wheel wagons with relation to a provision for tipping or dumping. Such provision as applied to a four-wheel wagon is not in itself new, my invention consisting in my peculiar construction for effecting the purpose; that is to say, my improvement consists primarily in supporting the body over the rear axle-tree upon springs running lengthwise of the wagon, when such springs are fixed to the body, and are so mounted as to have a capability of rocking movement upon the axle-tree, as will be herein explained.

The drawings represent a wagon embodying my improvement, A showing a reverse plan, B a side elevation, and C a rear elevation of the same.

a denotes the wagon body, *b* the front, and *c* the rear axle, supported respectively on the front and rear wheels *d e*. The rear axle-tree bed *f* is connected to the front transom-bar *g* by the perch *h*, and the body is so hung that its front partition board *i* comes directly over the transom-bar *g* and axle *b*, while the rear axle comes a little more than half way back to the rear board *k*. The body is directly supported on three springs, the front one of which, *l*, running transversely across the wagon, is permanently fastened to the transom *g*, and has the wagon resting loosely upon its opposite ends, and so as to tip up therefrom, when necessary, metal bearing-plates *m* being fixed to the wagon for the said ends to play upon, while the other two springs *n n* run lengthwise of the wagon, and have their ends secured to the body *a* by bolts *o* and loops *o'*, which permit the springs to expand lengthwise as the wagon body settles down upon them, but confine the body to the springs and truck. Fixed to the under side of each spring *n* at its centre is a plate, *p*, having vertical ears or projections, *q*, carrying a cross-bolt or journal, *r*, which rests in a socket-bearing or bed, *s*, on top of the axle-tree bed *f*, to which, and the axle, this socket-bearing is confined by suitable straps and screw-nuts *t*, the strap passing over each bolt and holding it down to its bearing, but allowing it to rock freely there. The springs *n n*, and with them the body thereto attached, rock freely upon the rear axle-tree by means of these journals and their socket-bearings, while the body is prevented from any twisting movement relatively to the rear axle, as will be readily understood. The wagon body is fastened down upon the front spring *l* by a chain, and an eye-bolt and hook, or by any other suitable locking or confining device, and in this position the wagon body is prepared for carrying any and all such materials as are transported either in common dumping-carts or in four-wheel wagons, while by loosening the chain the body may be readily tipped up on the rear axle, as shown by the red lines at B, to empty the contents thereof.

The wagon is designed particularly as a substitute for the ordinary two-wheel coal-carts, and combines with the advantages of a four-wheel spring-wagon, that which all dump-carts have, of being emptied of their contents by simply removing the back board and tipping the body on the axle. To support the seat *u* I extend the side boards *v* of the wagon body out beyond the axle-tree and beyond the front partition board *i*, as seen by dotted lines at B, and fasten the seat directly upon the top edges of the side and front boards, projecting the foot board out to correspond.

I claim the combination and arrangement of the body *a*, rocker-springs *n*, journals *r*, and socket-bearings *s*, together and relatively to the spring *l* and front and rear axles, substantially as described.

STEPHEN CHAMBERLIN.
